CLAIM

The ornamental design for a container for beverages or food, as shown and described.

DESCRIPTION

FIG. 1 is an upper left front perspective view of a container for beverages or food showing our new design in accordance with a first embodiment of the present invention;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top view thereof;
FIG. 7 is a bottom view thereof;
FIG. 8 is an upper left front perspective view of a container for beverages or food showing our new design in accordance with a second embodiment of the present invention;
FIG. 9 is a front elevation view thereof;
FIG. 10 is a rear elevation view thereof;
FIG. 11 is a left side elevation view thereof;
FIG. 12 is a right side elevation view thereof;
FIG. 13 is a top view thereof;
FIG. 14 is a bottom view thereof;
FIG. 15 is an upper left front perspective view of a container for beverages or food showing our new design in accordance with a third embodiment of the present invention;

(Continued)

FIG. 16 is a front elevation view thereof;
 FIG. 17 is a rear elevation view thereof;
 FIG. 18 is a left side elevation view thereof;
 FIG. 19 is a right side elevation view thereof;
 FIG. 20 is a top view thereof;
 FIG. 21 is a bottom view thereof;
 FIG. 22 is an upper left front perspective view of a container for beverages or food showing our new design in accordance with a fourth embodiment of the present invention;
 FIG. 23 is a front elevation view thereof;
 FIG. 24 is a rear elevation view thereof;
 FIG. 25 is a left side elevation view thereof;
 FIG. 26 is a right side elevation view thereof;
 FIG. 27 is a top view thereof; and,
 FIG. 28 is a bottom view thereof.
